UNITED STATES PATENT OFFICE.

WALTER S. MENDENHALL, OF NORWOOD, OHIO, ASSIGNOR TO THE SAMUEL C. TATUM COMPANY, OF CINCINNATI, OHIO, A CORPORATION.

PAPER-PERFORATOR.

SPECIFICATION forming part of Letters Patent No. 736,614, dated August 18, 1903.

Application filed May 13, 1903. Serial No. 156,863. (No model.)

To all whom it may concern:

Be it known that I, WALTER S. MENDENHALL, a citizen of the United States, residing at Norwood, in the county of Hamilton and State of Ohio, have invented certain new and useful Improvements in Paper-Perforators, of which the following is a specification.

My invention relates to a new and improved hand-operated paper-perforator.

10 The object is to provide a simple, convenient, and cheap construction with the least possible number of operative points.

The features of the invention are more fully set forth in the description of the accompanying drawings, making a part of this specification, in which—

Figure 1 is a front elevation of my device, partly in section. Fig. 2 is a side elevation. Fig. 3 is a section on line $\alpha\alpha$, Fig. 1.

20 A represents the base. B B represent the upright sleeves thereon, within which the punch members D D reciprocate.

C represents the female members under the punches D D.

25 E represents a cross-bar connecting and carrying the tops of the punches D D. Between the top ends of the sleeves B B and under the surface of the cross-bar E at each end are the coil-springs b b around the punches D D.

30 $\alpha\alpha$ represent the slits in the front sides of the sleeves B B for the insertion of the paper to be perforated.

F represents a bolt suspended from the bar E between the sleeves B B, having the headed lower end c.

35 G represents a stop secured to the base-plate by bolt f between sleeves B B, said stop having the forwardly-extending finger d, bifurcated at its end under the cross-bar and engaging bolt F above the head c. Obvi-

ously this stop is secured in position after the other members are assembled.

The punches are supported in the ends of bar E by means of heads g g. The coil-springs press upwardly the cross-bar and its 45 punches, holding them in position shown in Fig. 1 as limited by the engaging positions of the bolt and stop.

Having described my invention, I claim—

1. In a paper-perforator, a base, two upwardly-projecting sleeves, female punch members, transverse slits in the sleeves for presentation of paper, a cross-bar, punches in the ends thereof, fitting within said sleeves, a headed bolt suspended from the cross-bar, 55 a stop secured to the base under the cross-bar engaging the bolt above the head, and springs around the punches between the tops of the sleeve and the bottom of the cross-bar, holding in normal engagement the stop and headed bolt, substantially as described.

2. In a paper-perforator, a base, two upwardly-projecting sleeves having female punch members and transverse slits for the paper, a cross-bar, punches in the ends thereof, seating in said sleeves, springs around the punches between the tops of the sleeves and cross-bar exerting a lifting tension on the punches, and stop devices suspended from the cross-bar and supported on the base between the sleeves, adapted to limit the spring-actuated rise of the punches, substantially as described.

In testimony whereof I have hereunto set my hand.

WALTER S. MENDENHALL.
